William S. Sanderson. Troy, N.Y.
Letters Patent No 188, dated June 27 1848
(assigned to Anthony Dany & co.)

The schedule referred to in these letters
patent and making part of the same.

To all whom it may concern:

Be it known that I, William S. Sanderson of the City of Troy County
of Rensselaer & State of New York have inven-
ted or produced a new & original design, pat-
tern & configuration for the manufacture of par-
lor stoves, and I hereby declare that the following
is a full & exact description of the same, reference
being had to the accompanying drawings: viz, The
body of the stove is similar in shape to that of the
ordinary six plated stoves. The top side & end
plates & also the legs & the urn standing on the top
being ornamented with carvings of what is cal-
led perspective scroll work & in the peculiar
style & manner represented in the accompanying
drawings. And which drawings are to be taken as a
part of this description - Fig 1 represents in perspective
the whole stove as set up for use - "A" the front
plate ornamented with a vase of flowers in the center
& other fancy carved work exhibited in the plate, "B"
one of the end plates as ornamented "C" the top plate
D, the ornamented urn standing on the top. E.E.
the legs or feet of the stove - In fig 2 it's represents
more fully the shape of the carved figures on either
half of the top plate & "3" in like manner the figures
ornamenting the top of the urn.

What I claim as my invention and desire to secure by
letter patent is the peculiar style of ornamental
carving & scroll work on the outer surface of the
several plates of the stone, the Mtn & the leg. used
in the combination as herein set forth.
